UNITED STATES PATENT OFFICE.

CHARLES M. KENDALL, OF ILLIOPOLIS, ILLINOIS.

MANIFOLD-HEATER.

1,307,780.

Specification of Letters Patent. Patented June 24, 1919.

Application filed March 17, 1919. Serial No. 283,093.

To all whom it may concern:

Be it known that I, CHARLES M. KENDALL, a citizen of the United States, residing at Iliopolis, in the county of Sangamon and State of Illinois, have invented a new and useful Manifold-Heater, of which the following is a specification.

It is the object of this invention to provide a simple heater adapted to be applied to the intake manifold of an internal combustion engine, for the purpose of heating the mixture as it proceeds from the carbureter to the engine, it being a matter of common knowledge that it is somewhat difficult to start an automobile with cold fuel mixture.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the drawings:

Figure 1 shows in elevation, a portion of the fuel supply system of an automobile engine whereunto the device forming the subject matter of this application has been applied; Fig. 2 is an elevation showing the heater; Fig. 3 is a section on the line 3—3 of Fig. 2; and Fig. 4 is a section on the line 4—4 of Fig. 2.

In the drawings, the numeral 1 indicates the intake manifold of an internal combustion engine, the manifold having a neck through which the mixture proceeds to the manifold from the carbureter 3.

In carrying out the invention there is provided a heater in the form of a block 4, made of metal. On one side, the block 4 is provided with a longitudinal groove 5 formed by flanges 6 and 6^a, the flange 6^a being disposed approximately parallel to the longitudinal axis of the block, whereas the flange 6 is inclined at an acute angle to the said axis, the flanges 6 and 6^a, therefore, being disposed in converging relation with respect to each other. The upper ends of the

flanges 6 and 6^a are curved laterally, as shown at 7, and are extended longitudinally of the block and shaped, as indicated at 11 for a purpose which will be set forth hereinafter. The upper end of the block 4 is tapered as shown at 8 and merges into a hook 9, the inner curve of which is marked by the reference numeral 10, and it will now be observed, referring particularly to Fig. 3, that the curve of the hook indicated at 10, together with the parts 11 of the flanges 6 and 6^a, define a transverse groove 12 communicating with the longitudinal groove 5, the grooves being disposed at right angles to each other, both of the grooves 5 and 12 opening toward and through one side of the block. The hook 9 carries an upstanding lug 14 provided with a hole 15 adapted to receive a finger 16 on a rod 17 of any desired length.

In practical operation, the block 4 is placed, by means of the rod 17, in a stove, gas flame or other source of heat, the block being heated to any desired degree. Then, by means of the rod 17, the block may be placed on the manifold 1 and the neck 2, as shown in Fig. 1. The manifold 1 is received in the cross groove 12, the neck 2 being received in the longitudinal groove 5. The hook 9 projects beyond the outer edges of the flanges 6 and 6^a and serves to retain the block in place on the manifold. Owing to the particular configuration given the flanges 6 and 6^a and the ends 7 of the said flanges, the block will fit snugly about the neck 2 and the manifold 1, at the place where these parts are connected. Obviously, the heated block 4 will warm up the manifold and its neck 2, the charge being warmed accordingly before it is sucked into the cylinders of the engine.

Having thus described the invention, what is claimed is:

1. A heater of the class described, comprising a block having communicating longitudinal and transverse grooves, both of which are open at one side of the block.

2. A heater of the class described comprising a block having communicating longitudinal and transverse grooves, both of which are open at one side of the block, the transverse groove being formed, in part, by a hook having a lug provided with an opening.

3. A heater of the class described comprising a block having flanges defining a longitudinal groove, the block having a hook at

its upper end, the inner curve of the hook and the inner ends of the flanges being shaped to form a transverse groove communicating with the longitudinal groove, both 5 of the grooves being open at one side of the blocks.

In testimony that I claim the foregoing

as my own, I have hereto affixed my signature in the presence of two witnesses.

CHARLES M. KENDALL.
